UNITED STATES PATENT OFFICE.

WILLIAM R. WILSON, OF UNION CITY, INDIANA, ASSIGNOR OF ONE-HALF TO DELBERT T. WILSON, OF UNION CITY, INDIANA.

AUXILIARY AIR-INLET DEVICE.

1,306,987.

Specification of Letters Patent. Patented June 17, 1919.

Application filed November 6, 1918. Serial No. 261,404.

To all whom it may concern:

Be it known that I, WILLIAM R. WILSON, a citizen of the United States, residing at Union City, in the county of Randolph and State of Indiana, have invented a new and useful Auxiliary Air-Inlet Device, of which the following is a specification.

This invention aims to provide a simple means whereby an additional supply of air may be introduced into the fuel conduit of an internal combustion engine, the construction being such that no changes need be made in known parts, it being necessary merely, to clamp a simple plate between the carbureter and the outlet leading to the engine, the usual connecting bolts being employed.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings—

Figure 1 shows in section, a device constructed in accordance with the invention, parts appearing in elevation; Fig. 2 is a section taken approximately on the line 2—2 of Fig. 1; and Fig. 3 is a section taken through the device forming the subject matter of this application.

The numeral 1 denotes a carbureter and the numeral 2 marks an outlet member, leading from the carbureter to the cylinder of an internal combustion engine. The parts 1 and 2 are connected by bolts 3 or other securing elements, the construction above alluded to being common and well known.

In carrying out the invention, there is provided a carrier, in the form of a plate 4 having notches 5 in its ends, the notches being adapted to receive the bolts 3 which connect the carbureter 1 to the outlet member 2. Consequently, the plate or carrier 4 may be held between the carbureter and the outlet member by the usual instrumentalities whereby these parts are connected. The plate 4 has an opening 6 within which is lo-

cated a nozzle 7 having side perforations 8, the nozzle being held in place by means of an arm 9 formed integrally with or connected to the plate 4 at the edge of the opening 6. The nozzle 7 is held in place, further, by a pipe 10, communicating with the interior of the nozzle and mounted at its outer end in the plate. The pipe 10 may be alluded to as a conduit opening into the nozzle and opening through the plate. 65

The plate 4 is provided with a lateral projection 11, enlarged at its outer end, as shown at 12 to receive a hole 14. A pivot element 15 is mounted in the projection 11 and on the pivot element, a valve, in the form of a plate 16, is mounted to swing. The valve 16 is supplied with an opening 17 adapted to be brought into and out of registration with the outer end of the conduit 10. The valve 16 may be manipulated in any desired 75 way as, for instance, by means of a rod 18, mounted to slide in the hole 14 and pivoted at 19 to one end of the valve 16, the valve being fulcrumed, intermediate its ends, on the pivot element 15. The rod 18 is operated by any suitable means (not shown) from the dash board of a motor propelled vehicle, or elsewhere.

The valve may be swung on its fulcrum 15, to bring the opening 17 in the valve into 85 and out of registration with the outer end of the conduit 10, it being possible, by this procedure, to regulate the amount of air drawn through the conduit. From the conduit, the air passes into the nozzle 7, and it 90 is distributed through the perforations 8.

Owing to the provision of an additional air supply, as above described, a thorough combustion of the fuel will be effected, carbon deposits will be reduced, and, generally, 95 the efficiency of the engine will be enhanced. It is to be observed that the device forming the subject matter of this application is embodied in a simple plate adapted to receive the bolts 3, and to be clamped between the 100 carbureter 1 and the outlet member 2, no changes being wrought in existing and known internal combustion engine constructions.

Having thus described the invention, 105 what is claimed is:—

In a device of the class described, a plate having an opening therethrough; a hollow cup-shaped nozzle, the nozzle being closed at its outer end and being open at its inner end, 110

and having a laterally discharging perforation in its side wall, the axis of the nozzle being disposed approximately parallel to the axis of the opening, the periphery of the nozzle being spaced from the periphery of the opening to permit the passage of fuel longitudinally of the nozzle between the periphery of the nozzle and the periphery of the opening, the nozzle projecting beyond one side face of the plate; a single conduit forming a communication between the outer edge of the plate and the interior of the nozzle and embodying a pipe projecting into the opening, the pipe being assembled at one

end with the plate and being assembled at 15 its other end with the nozzle to support the nozzle; and a valve subject to manipulation by an operator and movably mounted on the plate at the outer end of the conduit, the valve constituting means for controlling 20 the passage of air into the conduit.

In testimony that I claim the foregoing as my own, I have hereto affixed my signature in the presence of two witnesses.

WILLIAM R. WILSON.
